FUEL INJECTION NOZZLE

Louis J. Garday, Sidney, N.Y., assignor to The Bendix Corporation, a corporation of Delaware

Filed Sept. 30, 1955, Ser. No. 537,651

6 Claims. (Cl. 239—533)

This invention relates to fuel injection apparatus for solid fuel injection engines and more particularly to fuel injection nozzles and spray tips therefor.

One of the objects of the present invention is to provide a novelly constructed nozzle for use in injecting liquid fuels into the combustion chambers of internal combustion engines and the like in a more desirable and efficient manner.

Another object of the invention is to provide a novel fuel injection nozzle which is so designed and constructed as to insure more efficient ignition and combustion in an engine of so-called diesel or solid fuel injection type.

Still another object is to provide a novel spray tip for a fuel injection nozzle which is particularly useful in combustion chambers wherein it is desirable to inject the fuel in the form of a wide cone-shaped spray and with less penetration into the compressed gases in the chamber than occurs with nozzles now in common use.

A further object is to provide novel means in a fuel injection nozzle for obtaining better atomization of the liquid fuel than is possible with known types of nozzles, such as the so-called pintle type nozzles, that discharge the fuel into the chamber in the form of a wide cone-shaped spray.

A still further object is to provide a novel spray tip unit for a fuel injection nozzle which is readily separable from the nozzle valve and holder assembly and hence, easily replaceable, thereby reducing the over-all cost of installing and maintaining fuel injection equipment of an engine or the like.

Still another object is to provide fuel injector spray tip assembly which is novelly constructed in such a manner that the same will produce a turbulent spray discharge, either coaxially with or at a desirable angle to the longitudinal axis of the nozzle holder with substantially equal effectiveness and efficiency, thereby permitting more convenient installation in a variety of engines.

The above and further objects and novel features of the present invention will more fully appear from the following detail description when the same is read in connection with the accompanying drawings. It is to be expressly understood, however, that the drawings are for the purpose of illustration only and are not intended as a definition of the limits of the invention.

In the drawings, wherein like reference characters refer to like parts throughout the several views,

Fig. 1 is a vertical sectional view of one form of fuel injection nozzle embodying the invention;

Fig. 2 is an enlarged sectional view of the spray tip embodied in the nozzle of Fig. 1; and,

Fig. 3 is a detail diagrammatic view showing a preferred form of spiral groove for the spray tip core.

The single embodiment of the invention illustrated, by way of example, in the accompanying drawing is shown in combination with a well known type of fuel injection nozzle valve and holder assembly comprising a nozzle holder body 10 which is externally threaded at one end to receive a tubular tip holder or sleeve nut 11 and

2

internally threaded at the opposite end to receive a nut 12. A valve guide or adaptor 14 abuts the lower end of body 10 and has a central bore coaxial with the bore through said body.

5 A valve 15 is slidable in the bore of adaptor 14 and has a reduced cone-shaped portion at one end which engages a valve seat 16 in a reduced bore portion of the adaptor. A chamber 17 surrounds the lower or reduced end of valve 15 and is connected with a suitable 10 supply of liquid fuel through a plurality of passages 18 and a groove 19 in adaptor 14 and a passage 20 in body 10. The upward or opening movement of valve 15 in response to pressure applied to fuel in chamber 17 is preferably limited by body 10 which is engageable by an annular shoulder on the valve.

A reduced upper end portion 21 of valve 15 extends into the bore of body 10 for operative engagement with a pressure rod or spindle 22. A spring 23 interposed between said spindle and nut 12 yieldably maintains valve 15 on its seat 16. Shims 24 may be provided within nut 12 for adjusting the tension of spring 23.

One form of novel spray tip assembly contemplated by the invention is supported by and projects from the lower end of nut 11. In the illustrated embodiment, this assembly comprises only two parts, one of which is a simply constructed casing 25 having an external flange 26 that is wedged between valve adaptor 14 and an internal shoulder in sleeve nut 11. The lower or outer end of casing 25 is preferably tapered or cone-shaped, and the interior of the casing is hollowed out to provide a cylindrical bore 27 and a cone-shaped bore portion 28 in the conical end thereof. An outlet of spray orifice 29 is cut through the end wall of the casing in a desired relation to the longitudinal axis of the casing and complete nozzle assembly. Orifice 29 is preferably, though not necessarily, cylindrical, and the internal wall thereof at the outermost end should make a sharp angle or edge with the outer end surface of casing 25. It is desirable to locate the inner end of orifice 29 near the apex of the internal conical wall surface 28. As shown, the axis of orifice 29 makes an angle of about 40 degrees with the axis of the casing, but these axes may make any other desired angle with each other, depending upon the circumstances of the installation on an engine or the like.

The other part of the spray tip comprehended and illustrated is a novelly constructed insert or core 30 secured within casing 25. A cylindrical portion 31 of the core has a tight, press fit in cylindrical bore portion 27 and preferably terminates flush with the end surface of casing 25 which engages the discharge end of valve adaptor 14. If desired, the casing and the insert or core may be spot or "heliarc" welded or otherwise suitably secured to one another. Intermediate its ends, the insert has a reduced or undercut portion 32 which provides an annular flow chamber 33. The remaining end portion of the insert has one or more, preferably two or three, spiral grooves 34 cut therein. The full diameter of insert 30 and hence, grooves 34, preferably terminate in or near the plane of the intersection of the walls of cylindrical bore 27 with conical bore portion 28, and if desired, the insert may have a reduced tip portion 35 which is illustrated as being conical. Between the end of core 30 and casing 25, there is thus provided a cone-like chamber 36 which communicates with a combustion chamber or the like through orifice 29 and may be suitably referred to as a turbulence chamber. The transverse sectional shape of grooves 34 is preferably that which is illustrated in Fig. 3, and the radial depth of the grooves is preferably slightly greater than the depth of the undercut forming reduced section 32 of the insert. In the latter case, each of the grooves should

run out in the surface of the undercut portion, as illustrated at 37, and the lands at the discharge ends of the said grooves at the end adjacent chamber 36 should be sharp to insure a turbulent swirling motion of the fuel discharge from the grooves into the turbulence chamber.

Insert 30 has a central fuel passage 38 extending into the undercut portion 32 thereof and connected by one or more radial ports 39 with annular chamber 33. Fuel which passes valve 15, 16 thus flows through passages 38 and 39, annular chamber 33, spiral grooves 34, turbulence chamber 36, and outlet orifice 29 into a combustion chamber. As mentioned above, a turbulent, swirling motion is imparted to the fuel as it passes through grooves 34 into the largest diameter end of turbulence chamber 36. As the swirling fuel approaches orifice 29 along the converging walls of chamber 36, the radius of the swirling path of the fuel is gradually diminished. It is believed that the swirling motion continued at a very high speed within the outlet orifice 29 so that as the fuel leaves the orifice a relatively wide cone-like spray of well atomized fuel results, the axis of the spray being coincident with the axis of the orifice.

The type of spray thus produced has comparatively short penetration and is very desirable in certain types of combustion chambers. The extent or degree of penetration, as well as other characteristics of the ejected fuel and its pattern, may be controlled by varying the velocity of the fuel flow and hence, the turbulence thereof, by varying the directional angle or pitch of the spiral grooves 34, by varying the diameter of the turbulence chamber and the taper of the walls, thereof, or by varying the wall thickness at the end of casing 25 and hence, the axial length of orifice 29. Everything else being equal, a large angle between the axis of the spray tip assembly and the axis of orifice 29 or a relatively large diameter swirl chamber will produce better dispersion, higher line pressures and less penetration. The turbulence velocity may be controlled by varying the flow areas through the spiral grooves in relation to the flow area of the outlet orifice 29. The total flow area through the spiral grooves 34 should be considerably in excess of the flow area through orifice 29 in order to insure unrestricted flow through the spiral grooves. It has been found that the uniformity of dispersion and atomization is influenced by the number of spiral grooves, greater uniformity being attained with a greater number of grooves.

There is thus provided a novel spray or discharge tip assembly for a fuel injection nozzle of the type used in solid fuel injection engines or in nozzles for spraying other types of liquids for a variety of purposes.

The construction contemplated is simple, comprising only two relatively simple parts which may be readily and quickly assembled. The device is also readily replaceable in a complete nozzle assembly, thereby rendering it easy to obtain most efficient operation at minimum cost.

Although only a single embodiment of the invention has been illustrated in the accompanying drawings and described in detail in the foregoing specification, it is to be expressly understood that the invention is not limited thereto. For example, the outer wall of the turbulence chamber may be arcuately concave or partially concave and partially conical as distinguished from cone-like, as illustrated in the drawing. The same is true of the tip 35, the surface of which may be arcuately convex or somewhat spherical. Also, the spiral grooves or channels by means of which the liquid is discharged with a swirling motion into the turbulence chamber may be formed by internal threads in the bore or counterbore of shell 25, and fuel may be supplied to annular flow chamber 33 through channels at the periphery of core piece 30 instead of through the central and radial passages illustrated. Various other changes may also be made, particularly in the design and arrangement of parts illustrated, without departing from the spirit and scope of the

invention as the same will now be understood by those skilled in the art.

What is claimed is:

1. In a liquid spray nozzle, a shell having a longitudinal counterbore therein and a core means in said shell, said core means and shell cooperating to form an annular flow chamber, a turbulence chamber at and extending transversely entirely across the inner end portion of the counterbore, and at least one spiral passage connecting said annular flow chamber to said turbulence chamber, said shell having a discharge orifice in the end thereof communicating with the turbulence chamber adjacent the longitudinal axis thereof, the axis of said orifice extending at an angle to the longitudinal axis of said counterbore and at approximately a right angle to the surface of the wall of said turbulence chamber at the inner end of said orifice.
2. Apparatus as defined in claim 1 wherein the end wall of the counterbore forming a wall of said turbulence chamber tapers to the longitudinal axis of the counterbore and the discharge end of said spiral passage is at the periphery of the largest diameter end of said tapering wall of the turbulence chamber.
3. Apparatus as defined in claim 2 wherein said core means has a central tip portion forming a wall of said turbulence chamber, the surface of which tip portion converges to said axis in the same direction as the tapering end wall of the counterbore, the intersection of said axis and said end wall being in spaced relation to the free end of said tip portion.
4. Apparatus as defined in claim 3 wherein the end wall of the counterbore and the surface of said tip portion diverge with respect to each other in the direction of said discharge orifice.
5. A spray tip for a fuel injection nozzle or the like comprising a shell having a bore terminating near one end thereof, and core means in said shell extending into spaced relation with the inner end of said bore, said shell and core forming a chamber at the inner end of said bore, the end wall of the bore forming said chamber converging toward the longitudinal axis of the bore at an acute angle, an annular flow chamber, and at least one spiral channel at the periphery of said bore connecting said chambers, said shell having an outlet orifice in said one end thereof, the inner end of said orifice being adjacent the longitudinal axis of said bore and the axis of said orifice extending at an angle to the longitudinal axis of said bore and at approximately a right angle to the surface of said end wall at the inner end of said orifice, and said core means having a central tip portion extending into said first-named chamber beyond the discharge end of said spiral channel, the surface of which tip portion converges at the longitudinal axis of the bore at an acute angle thereto, the angle of convergence being greater than the angle of convergence between the axis and the end wall of said bore, whereby the surface of said tip portion and the end wall of said bore in said first-named chamber diverge from each other toward the apex of said chamber.
6. A spray tip for a fuel injection nozzle or the like comprising a shell having a bore terminating near one end thereof, and core means in said shell extending into spaced relation with the inner end of said bore, said shell and core forming a chamber at the inner end of said bore, the end wall of the bore forming said chamber converging toward the longitudinal axis of the bore at an acute angle, an annular flow chamber, and at least one spiral channel at the periphery of said bore connecting said chambers, said shell having an outlet orifice in said one end thereof, the inner end of said orifice being adjacent the longitudinal axis of said bore and the axis of said orifice extending at an angle to the longitudinal axis of said bore and at approximately a right angle to the surface of said end wall at the inner end of said orifice, and said core means having a central tip portion extending into said

first-named chamber beyond the discharge end of said spiral channel, the surface of which tip portion converges at the longitudinal axis of the bore at an acute angle thereto.
